CARL F. E. OLOFSON, OF WEST ORANGE, AND NILS O. LINDSTROM, OF NUTLEY, NEW JERSEY, ASSIGNEES TO A. B. SEE ELEVATOR COMPANY, INC., A CORPORATION OF DELAWARE

ELECTRIC ELEVATOR SYSTEM

Application filed December 6, 1927. Serial No. 238,010.

Our invention relates to an electric elevator system which is particularly adapted for high speed elevators. According to present practice the operating speed of electric elevator cars is very high, as much as seven hundred feet per minute and sometimes even more. This means that less than one second elapses between floor landings when running at full speed. It is necessary, however, 10 to be able at any time to bring the car to a stop within a short distance without causing any unpleasant sensations of jarring, etc. to the passengers and the stop must be made with a high degree of accuracy as regards the floor levels of the car and landing. Although the loads upon the hoisting motor and the momentum of the moving car vary greatly, depending upon the number of passengers in the car, the control mechanism 15 must be able to cause a quick stopping of the car with its floor at the same or very nearly the same level as the landing.

In slow speed elevator work it has been possible for the operator, especially after 20 he has become an expert, to sometimes make a stop with a fair degree of accuracy by direct hand control of the driving means, but even in such apparatus it has been the usual practice for the operator to resort to "inching" to bring the car to the landing after 25 making an initial stop in which he usually overruns or underruns the landing depending upon the momentum of the car and its position when he initiates the stopping.

Such inching or levelling operations are wasteful both of current and time and accordingly efforts have been made to minimize such losses in both high and slow speed elevator systems by providing means for 30 automatically stopping the car and for automatically levelling it after it has been brought to an initial stop. These devices however, still incur losses of current in the levelling operation.

The present invention, while perfectly adapted for slow speed elevator control, has been devised more particularly to meet the requirements of high speed elevator practice and has for its primary object the provision of automatic slow down and stop 40

mechanism of such range and accuracy with varying loads as to effect the desired landing without the action of auxiliary levelling devices or inching by hand control, (although such may be used if desired) whereby the losses above referred to are avoided. Another object of the invention is to provide elevator control means in which there are no cams or switches in the hatchway intermediate the usual cams at top and bottom. 45

The improved apparatus will work accurately with the highest elevator speeds now in use. It comprises a minimum number of moving parts and the apparatus throughout 50 is of such simple character both mechanically and electrically as to operate with perfect safety to passengers and over long periods of time without breakage or undue wear; and it is free from defects which might 55 cause failure to operate either at all or with the speed necessary to success.

Reference is hereby made to the accompanying drawings, of which:

Fig. 1 is a diagrammatic view of the improved elevator system as a whole; 75

Fig. 2 is a similar view showing on an enlarged scale the traveling and fixed contacts and the connection of the latter with the rotary switch, and

Fig. 3 is a detail view of the means for driving the screw shaft and rotary switch.

The particular form of apparatus to which we have shown our invention applied is an elevator driven by the Leonard system, viz 80 a line motor, a generator directly connected thereto and a hoisting motor driven by the generator, but it may be used with other forms of drive.

Referring to Fig. 1, the line wires 1 and 2 are connected with the shunt wound direct current motor M and the generator G is driven thereby, its armature being in series 85 by means of wires 1' and 2' with the armature of the hoisting motor N, the field q' of said motor being separately excited from the line wires 1 and 2 through the leads 3' and 4'. The elevator car C is suspended by the usual cable and provided with counterweight E, the same being operated by the 90 100

hoisting motor N. Means are provided whereby the movement of the car C causes a corresponding movement on a reduced scale of a plurality of traveling contacts for controlling the slowing down and stopping of the car, and associated with the said contacts are a plurality of series or sets of fixed contacts. Each series consists of one contact corresponding to each floor landing which is to be served by the elevator, and there are as many series of such fixed contacts as there are traveling contacts just referred to. For convenience only two contacts of each series of fixed contacts are shown. The paths of the traveling contacts are such as to cause them to engage successively with the fixed contacts constituting a single series. There is also a rotary switch comprising a plurality of fixed contacts which are respectively connected to the fixed contacts of certain of said series which have been just described and a rotary contact so connected as to apply current to the various switch contacts at the proper time to carry out the purposes of our system as will be more fully described.

In order to cause the desired movement of the traveling contacts and rotary switch, any form of gearing may be used which will cause the same to travel in a manner corresponding to the movement of the elevator car. The mechanism which we prefer to employ comprises an endless strip or band F which is attached at one point to an arm G' carried by the car. The band F is an endless steel ribbon or tape having holes 85 punched therethrough at equal intervals. The band F travels over a suitably supported sheave H at the top of the shaft and a sheave I is supported by the band F at its lowest point and is held in position by the weight J. The sheave H is provided with pins 86 secured thereto at equal intervals along its periphery as shown in Fig. 3. Said pins engage the holes 85 of the band F. The sheave H is driven by the band F and drives the horizontal shaft K which by means of a bevel gear L in engagement with similar gears O and P, causes the rotation of the switch arm Q' and vertical screw shaft R. There is a carriage S having a hub which is internally threaded and engages the thread of the shaft R so that rotation of the latter causes vertical movement of the carriage S either up or down, the usual arrangement being such that the carriage S will be at the bottom of its path when the elevator car is at the bottom of the shaft, and will travel upward in accordance with the upward movement of the car so that it will reach the top of its path when the car reaches the top of the shaft, but obviously one may if he desires arrange the gearing so that the carriage will be at the bottom of its path when the car is at the top of the

shaft, and the carriage will be at the top when the car is at the bottom. The movement of the carriage is greatly reduced as compared with that of the car. For ordinary purposes such reduction may be as much as twenty to one, or more or less for the sake of convenience.

The various series of fixed contacts before referred to, which contacts are herein designated as a', are mounted upon vertical bars which are parallel to the shaft R and are so arranged that the various contacts a' will be engaged during the movement of the carriage S by the traveling contacts b', b², b³ etc. which are preferably rollers carried by pivotal arms supported by the carriage S and adapted by spring pressure to make suitable contact with the fixed contacts a' during their travel. It will be noted that although the elevator car may be traveling at a very high velocity the reduction in speed of the carriage S with respect to the car is so considerable that the speed of the carriage will be suitable for the engagement of the fixed and traveling contacts and the functions which they perform will be readily carried out and without danger of failure.

In the apparatus illustrated we have shown the contacts a' applied to five vertical bars on each side of the vertical shaft R, those on the left relating to the controlling of the car when moving in an upward direction, and those on the right for performing similar functions when the car is moving downward. These five bars are designated respectively c', d', e', f' and g' for the upward movement, and c², d², e², f² and g² for the downward movement. For the sake of convenience we have shown only two of the contacts a' on each of these bars, but it will be understood that there will be a separate contact corresponding to each landing, that is, if there are ten floors or landings there will be ten contacts a' on each of the bars c', d', c², d², etc. The bars c', d', c² and d² are conductive and each of the contacts a' which are carried thereby is in electrical contact therewith. The bars e', f', g' and e², f², g² are insulated with respect to the contacts a'.

The rotary switch Q which may be in form somewhat similar to a commutator is built up of a large number of fixed segments h' which are insulated from each other. This switch is provided with a rotating contact arm Q' which is adapted to contact successively with the various segments h' during the travel of the elevator car. Inasmuch as this arm is geared to and driven by the elevator car, any definite position of the car in the shaft corresponds to a definite position of this arm. The gearing may be such as to cause the arm to make two rotations for each floor covered by the car, that

is, while the car travels from one landing to the next, but the rate of travel of the arm and the number of segments h' are capable of wide variations.

- 5 In the device illustrated there are 84 segments, and since the arm rotates twice as the car travels from one floor to the next, the distance between centers of adjacent segments h' will correspond to less than one 10 inch of travel of the car, assuming floor levels to be eleven feet apart. This provides a very fine adjustment for the moment or instant of energization of the various slow down means, for the reason that the contacts a' on bars $e', f', g', e^2, f^2, g^2$, being all insulated with respect to each other can be connected by their leads with any of the segments h' and in practice each contact a' will be connected to the particular segment 15 h' which will be contacted by the arm Q' at the proper moment for the energization of the slow down means controlled by the contact a' in question. Each of the contacts a' may if desired be adjustably mounted upon 20 its supporting bar c', d', e' etc. so that its position may be varied in a vertical direction, but such adjustments may be dispensed with by reason of the adjustment provided by the large number of segments h' to any 25 30 one of which the contact a' may be connected by its lead. This range of choice also becomes useful in case of irregularities, for instance variations in the distances between landings, which might, for example, cause or 35 tend to cause the car in ascending to stop too far below some particular landing. In such case all that is necessary to do to correct the trouble is to detach the conducting wires of the appropriate contacts a' of bars 40 45 50 e', f' and g' from segments h' and connect them to segments h' sufficiently in rear thereof to delay the action of the slow down means by the desired interval to cause a satisfactory stop. In practice it will usually be necessary in adjusting for irregularity to reconnect with a segment h' only the contact a' or bar g' .
- It will sometimes happen that many of the segments h' will not be connected to any of the contacts a' . For example, let us assume that the landings are all equidistant and that the arm Q' makes exactly two turns per landing then all of the leads from the 55 various contacts a' of bar g' will be connected to the same segment h' , that is there would be but a single lead from all of these contacts a' to segment h' , and similarly with respect to the contacts of the other bars e', f', e^2, f^2 and g^2 so that only six of the eighty-four segments would be in actual use. But if the arm Q' should make $2\frac{1}{16}$ rotations per landing the successive contacts a' of bar g' will be connected to segments h' which occur at intervals of 36° around the switch,

and similarly with respect to the contacts a' of the other bars e', f' etc.

Control means are provided upon the elevator car whereby the operator is able at any desired time to bring about the operation of the various instrumentalities for the slowing up and stopping of the car in traveling either at a medium or very high rate of speed, the stopping being accomplished rapidly but smoothly without discomfort to the passengers and in such a manner that the floor of the car will occupy a position which practically coincides with the floor of the landing so that the use of automatic or hand levelling devices may be dispensed with. Any suitable form of control switch or switches may be used, but we prefer to use the form shown which is disclosed and claimed in an application of Nils O. Lindstrom, Serial No. 205,288, filed July 13, 1927. 70 This device, C', comprises a lever member e having a conducting sector 87 insulated therefrom. Groups of contact fingers a, b, c, a^2, b^2 and c^2 are provided to cooperate with sector 87 for the control of appropriate circuits. The lever e is provided with an operating handle d which is constructed for a sliding movement in a forward direction i. e. parallel to the axis upon which the lever e is mounted. The handle d comprises 80 a pin member (not shown) for actuating circuit closing arms or contacts h', h^2 when the handle is pushed in a forward direction as described. In order to avoid repetition of the electrical connections to the various devices for controlling the speed and stopping of the elevator will be pointed out in connection with the following description of the manner of operation. 90

The current from line wire 1 passes 105 through wire 3 to point a of car controller C' and upon movement of the controller arm e and sector 87 a is connected to controller point b and through wire 5 energizes the magnet coil f of reversing switch U for 110 upward movement. From coil f the current passes through wire 4, slow speed up limit switch g , wire 6, wire 8, arm i^2 of normally closed switch i and wire 10 to line wire 2, thus completing the circuit. The effect of 115 such energization of this circuit is the closing of the reversing switch U. This closes a circuit through the magnet n of the hoisting motor brake by which the brake is removed from the motor shaft, the circuit being as follows: Line wire 1, wire 3, points k and m of reversing switch U, wire 7 to magnet n and returning by wire 12 to points o and p of reversing switch, wire 14, wire 120 125 10, to line wire 2.

The closing of the reversing switch U also energizes the field of the generator G through the following circuit: Wires 1 and 3, points k and m of reversing switch U, arm r' of said switch, wire 9 to field wind- 130

ing q returning by wire 16, resistance s , wire 18, normally closed switch arm t^3 , wire 20, normally closed switch arm t^4 , wire 22, pivotal arm r of reversing switch U, switch 5 points o, p , wire 14, wire 10, to wire 2.

The car is, therefore, by reason of the movement of the controller handle to connect point a with b , caused to start and move in an upward direction at a low speed due to 10 the fact that the resistance s is in series with the field winding q of the generator G. If at this time the operator should move the handle back to its normal or off position, he would merely deenergize the magnet f of 15 the reversing switch U which would stop the car by opening the circuit through the generator field winding q and cause the application of the brake to the hoisting motor by reason of the opening of the circuit through 20 the magnet n , these functions being brought about by the opening of the reversing switch U and being merely the opposite of what took place when the switch was closed.

The operator, however, will ordinarily 25 after moving the controller handle d to the point b , continue the movement of the handle so as to cause the energizing of the point c . The effect of this connection is the establishing of a current through the following circuit: From line wire 1 and wire 3 to controller point a and through sector 87 to point c , thence through wire 11 to normally closed switch arm 13 of triple arm switch v , contact 13_s , wire 15, normally 30 closed arm 17 of triple arm switch w , contact w^2 , through magnet coil of switch z , wire 24, high speed up limit switch y , wire 26 to the downward extension of arm r of reversing switch U, points o, p , and wires 40 14 and 10, to line wire 2.

The effect of the energizing of magnet of switch z is the shunting of the resistance s by closing a path from wire 16 to arm t^3 of switch t through wire 28, arm 30, and wire 45 32. The effect of this shunting of resistance s is to apply the full line voltage to the field winding q of the generator G and thereby cause it to deliver its maximum voltage to the hoisting motor N and therefore operate the elevator at maximum speed. 50

This increased generator voltage which is applied to the wires 1' and 2' also affects a magnet z' through the wires 5', 6'. The magnet z' is designed to throw the triple 55 arm switch z when the elevator car reaches a high rate of speed which will correspond to a high voltage in wires 1', 2', 5' and 6'. In practice this magnet has been arranged to throw the switch arms c^3, c^4 and c^5 60 to the left at 200 volts and permit them to move to the right at 150 volts. These values are merely illustrative and will vary with different apparatus. The three pivotal arms c^3, c^4 , and c^5 of the switch z normally occupy the position shown in the draw- 65

ings, but when the switch magnet z' is energized as just described these three arms are moved to the left sufficiently to open the circuits which include the pivotal arms z^2, z^3 and z^4 and contacts a^2, a^3 and a^4 . Furthermore the effect of the movement of the arms c^3 and c^4 to the left from the position shown is to cause the same to connect the pivotal arms z^2 and z^4 with the fixed contacts a' upon the respective bars c' and c^3 75 for the purpose which will be later described.

The elevator car is at this time traveling at high speed and while the operator may at any time reduce its speed and bring it to stop by manual operation of the controller arm in a direction reverse to that for speeding up the car, he will ordinarily bring about the stopping of the car automatically 80 so that the car will be stopped in a minimum space of time and with exactness as regards the floor of the landing. This automatic action will be initiated by the operator by pushing the handle d of the controller arm in a forward direction so as to close the 85 contacts h^1, h^2 . This causes the energization of the wire 21 and a circuit is established through resistance v^1 and magnet coil v^2 of switch v , thence through wires 34 and 10 to line wire 2. The effect of the closing circuit 90 is a partial energization of the magnet coil v^2 . On account of the resistance v^1 being in series with this coil, the energizing current is not sufficient to cause the switch arms v^3, v^4 and v^5 to be thrown. The switch, 95 however, is brought into such condition by this partial energizing that when additional energization is applied to the coil v^2 the switch arms will be very quickly thrown. In other words it makes the switch very 100 quick acting.

Another effect which follows from the engagement of controller contact h^1 with h^2 and which causes the energizing of wire 21, 105 is the energizing of wire 23 which energizes contacts b' and b^2 which are carried by the traveling carriage S. This means that as soon as the roller b' contacts with the nearest of the contacts a' which it is then approaching, it will complete a circuit through the wire 23 just referred to, contacts b' and a' , and bar o' , wire 25, arm o^s of switch z , arm z^2 wire 27, coil v^2 of switch v and wires 34 and 10 to line wire 2. The effect 110 of the closing of this circuit is very quick action of the magnet v^2 by reason of its already being partly energized, and the throwing of the three switch arms v^3, v^4 and v^5 from the position shown so as to contact respectively with the arms 13, 13₁ and 13₂. The effect of the movement of the arm v^5 to the left is the separation of the contact arm 13 from the contact 13₁ and the opening of the circuit through the magnet z by way of the wires 11, 15, 19, 24, 26, r, o, p , 115 120 125 130

14, 10 and 2 which has been previously described. This deenergizing of the magnet ω causes the arm 30 to move to the right into open circuit position thereby opening the shunt which had been connected across the field resistance s whereby the latter resistance is now placed in series with the field winding q . The voltage delivered by the generator G to its line wires 1', 2' rapidly falls and the speed of the hoisting motor N accordingly diminishes. The decrease in voltage between wires 1' and 2' causes a drop in voltage between 5' and 6' and a partial deenergization of magnet z' . When such voltage drops to approximately 150 volts, the magnet is no longer able to hold the switch arms c^3 , c^4 and c^5 in contact with arms z^2 , z^3 and z^4 , and said arms are therefore thrown to the right into the position shown. The effect of this movement is to cause z^2 to contact with a^2 whereby the energization of the contact bar c' which was formerly effected through wire 25 and arm c^3 is transferred to contact bar d' through wire 29, contact a^2 , arm z^2 , wire 27, coil v^2 and wires 34 and 10 to line wire 2. In other words it means a substituting of the contact bar d' for action instead of c' so that when the traveling contact roller b^2 contacts with the nearest of the fixed contacts a' which it is then approaching, it will establish a circuit through the magnet v^2 of the switch v and hold the contacts v^3 , v^4 and v^5 in their left-hand position, maintaining them as they were, the circuit being in the nature of a holding circuit for this purpose.

When the magnet z' becomes sufficiently deenergized to permit the arm c^5 to move to the right into the position shown, circuits will be closed for the partial energization of the magnets t and u which control the introduction of resistances into series with the field winding q of the generator G. This current will not be sufficient to cause the operation of the switch arms t_1 and t_2 , but will cause the magnets when further energized during a later sequence of operations to act very quickly. These circuits for the partial energization (in multiple) of said magnets t and u are as follows: From wire 3 through wire 31, switch arm z^4 , contact a^4 , wire 33, resistance 35, wire 37, magnet coil u , wire 36, wire 38, arms 13₁, and v^4 of switch v and wire 40 to wire 34, and thence through wire 10 to line wire 2. The circuit in multiple therewith through coil t is from wire 33, through resistance 39, wire 41, magnet coil t to wire 38, thence to the line as before described.

The next step in the slowing down of the elevator is produced by contacting of traveling contact b , with fixed contact a' on bar e' . This closes a circuit through magnet coil t whereby a shunt formed by wires 18 and 20

will be opened thereby placing resistance s' in series with field winding q and resistance s . The circuit by which this is effected is as follows: From line wire 1 and wire 3 through wire 31, switch arm z^4 , wire 33 to the traveling arm Q_1 of rotary switch Q , thence through segment 43 of said switch to wire 45 and contact a' of bar e' , roller contact b^3 , wires 47 and 41 to magnet coil t , thence through wire 38, arms 13₁ and v^4 , wires 40, 34, and 10, to line wire 2.

The next step in slowing down is the energizing of coil u which moves the arm t^2 to the left sufficiently to operate the arm t^4 and open a shunt circuit through wire 20², arm t^4 and wire 20', whereby resistance s^2 will be placed in series with field coil q of generator G and resistances s and s' , thereby reducing the voltage generated thereby and slowing up the motor N. This circuit is similar to the one just described, except that in this case the rotating switch arm Q' makes contact with segment bar 49 and the current passes through wire 51 to contact a' on bar f' whence it passes through traveling contact b^4 to wire 53, wire 37, coil u , wires 36, 38, switch arms 13₁, v^4 , wires 40, 34 and 10 to line wire 2.

The final step in the stopping of the elevator is the opening of the circuit through the magnet f of the reversing switch whereby the same is deenergized and the switch is thrown into its open circuit position. The circuit for accomplishing this function is as follows: When the traveling switch arm Q_1 reaches the segment 55 it energizes the wire 57 and contact a' carried by the vertical bar g' and when the same is engaged by traveling contact b^5 the current passes through wire 59 to switch arm 13₂ of switch v , thence through arm v^5 , wire 61 to magnet coil i which causes arm i_1 to move to the left sufficiently to separate arm i_2 from contact i_3 , the circuit being completed through wire 10, to line wire 2. The opening of a circuit by separating i_2 and i_3 deenergizes magnet f of reversing switch U causing this switch to be opened and thereby opening the circuit through the field coil q of the generator G and also deenergizing the brake magnet n of the hoisting motor.

By the series of operations brought about automatically by reason of engagement of the traveling contacts carried by the carriage S with the fixed contacts mounted on the vertical rods c' , d' , e' , f' and g' , the car will be brought to rest exactly on a level with the landing or so close thereto as to be practically at the same level. It should be noted that the arrangement is such that while the operator will customarily push the controller handle d to stop the car just before reaching the landing ahead of the one at which he desires to stop, in case he should be a little

late in pushing the handle so that the traveling contact b' of the carriage S has gone too far to engage the desired contact a' upon the bar c' , the car will not then stop 5 at or near the desired floor but will proceed to the next floor for the reason that the contacting of the traveling contacts b^2 , b^3 , b^4 and b^5 with the fixed contacts a' upon the bars d' , e' , f' and g' will be ineffective 10 by reason of the high speed of the car. The magnet z' by holding the arms c^3 , c^4 and c^5 in left-hand position will cause the circuits for the energizing of such fixed contacts to remain open. In other words, if 15 the operator is too slow in his operation of the controller handle, he will not make a poor landing, that is, a landing in the wrong position with respect to the desired floor, but the car will be carried to the floor above 20 and stopped in an accurate position with regard to such floor as this is considered preferable to making an imperfect landing, and, of course, such overrunning will occur 25 only when an error is made by the operator. In such case the car can easily be brought back to the desired floor by hand operation of the controller arm.

In the above description of the operation of the automatic slow down and stop means 30 we have assumed that the elevator was travelling at high speed with voltage across wires $5'$, $6'$ sufficient to fully energize the magnet z' and throw the arms c_3 , c_4 and c_5 to the left. In practice the elevator car will 35 attain such speed only in case it travels farther than from one landing to the next. In case it is desired merely to run from one floor to the next the operator will proceed exactly as before as regards the movements 40 of controller handle d , and the car will nevertheless be brought to an accurate stop although the magnet z' will not be sufficiently energized to throw the arms c_3 , c_4 and c_5 to the left since the voltage across wires $5'$ 45 and $6'$, and which varies with the speed of the car, will not be great enough for such energization. For this reason the arm z_2 remains in contact with a_2 which means that the contacts a' of bar d' are connected with 50 line wire 2 through wire 29, a_2 , z_2 , 27, coil v_2 , 34, and 10. Therefore as soon as roller b_2 engages the nearest contact a' of said bar d' the magnet v_2 will be energized and move arm v_2 to the left to separate 13 and 13₃ and 55 deenergize magnet z and thereby insert resistance s in series with generator field coil q and slow down the hoisting motor and elevator car. The further slowing down and stopping of the car will be accomplished 60 as previously described by the successive engagement of rollers b_3 , b_4 and b_5 with contacts a' of the respective bars e' , f' and g' .

From this it is seen that the contacts a' of bar d' perform two functions: (1) In 65 case the car is running at full speed at the

moment the operator pushes forward the controller handle d the said contacts will at that time be disconnected from line wire 2 and magnet v_2 by reason of arm c_3 holding arm z_2 away from contact a_2 and they will 70 be incapable of energizing the magnet v_2 even though they should be engaged by contact b_3 . They remain inactive until the speed of the car has dropped (by reason of engagement of roller b' with contact a' of bar c') to the rate corresponding to a voltage (for example) between wires 1' and 2' of 150 volts, at which time magnet z' releases arm c_3 and allows arm z_2 to engage 75 contact a_2 . Such engagement energizes the 80 contacts a' of bar d' and causes the same when engaged by roller b_2 to maintain a current through magnet v_2 thereby causing arm 17 and contact w_2 to remain separated and magnet z deenergized until the beginning 85 of the sequence of operations controlled by contacts a' of bars e' , f' and g' . After such sequence has started the energizing of magnet coil z would be ineffective 90 to shunt the resistance s , because of the successive opening of the shunt circuit at t_3 and t_4 , followed by action of magnet coil i which causes the opening of the reversing switch 95 U. In practice the operator after pushing 100 forward the controller hand d to cause an automatic stop will as soon as the car begins to slow up return the handle d and arm e to their initial or off positions, which would of itself prevent magnet z from receiving any 105 energizing current through wire 11 even though switch magnet v_2 be deenergized. (2) In case the car is running at comparatively low speed at the moment the operator pushes forward the controller handle d , as for instance in running only from one floor 110 to the next, the voltage across wires $5'$ and $6'$ will be insufficient to cause magnet z' to move arms c_3 , c_4 and c_5 to the left and therefore the contacts a' of bar d' will be energized instead of those of bar c' and the energizing of magnet v_2 and deenergizing of z will be caused by engagement of roller b_2 with contact a' of bar d' instead of engagement of roller b' with contact a' of bar c' as previously described for a stop when 115 running at full speed.

The principle of operation of the various parts concerned in operating the car in a downward direction is the same as in the upward movement. It, therefore, will be necessary only to point out the various circuits by which the movement of the elevator in a downward direction is controlled.

The controller point a^s is energized from 125 wire 3 and the movement of the controller handle to the right will cause the sector 87 to bridge the gap between a^s and b^s and thereby cause a current to flow through wire 63 to magnet f^s of reversing switch D, thence through wire 42, slow speed down 130

- limit switch h to wire 8, contact t^3 , switch arm t^2 and wire 10 to line wire 2. The energizing of the magnet f^8 closes the reversing switch D, by which the following circuits are closed: namely, (1) from wires 3, through contacts k^3 and m^3 , wire 7 to brake magnet n , returning by wires 12 and 44, contacts o^3 and p^3 , wire 46, wire 10 to line wire 2; also (2) through wires 1 and 3, contacts k^3 and m^3 , switch arm r^3 , wire 22, thence through wire 20', arm t^4 of switch u , wire 20, arm t^3 of switch t , wire 18, resistance s , wire 16, field winding g of generator G, wire 9, switch arm r^4 , contacts o^4 , p^4 , and wires 46 and 10 to line wire 2. The flow of current in this circuit being in the opposite direction from that previously described causes a reversal in polarity of wires 1', 2' and rotation of the hoisting motor N in a reverse direction, which means a downward movement of the car instead of upward, and on account of the resistance s being in series with the winding g the movement is at a reduced speed.
- 25 When the operator moves the controller handle to the next position whereby point c^4 is energized, a current is established through wires 1 and 3, contacts a^3 and c^3 , wire 11, switch arm 13, contact 13₃, wire 15, arm 17, contact w^2 , wire 19, magnet x , wire 24, high speed down limit switch y^3 , downward extension 48 of arm r^4 of reversing switch D, contacts o^3 and p^3 , wires 46 and 10 to line wire 2. The energizing of magnet x causes a closing of arm 30 and therefore a shunting of resistance s by means of the wires 32, arm 30 and wire 28, whereby the current through the field winding g is increased, the voltage of the generator G rises and drives the hoisting motor N at increased speed. The increased voltage on the generator line wires 1', 2' increases the energization of the magnet z' sufficiently to throw the arms c^3 , c^4 , c^5 to the left. This causes the arm c^4 to effect a separation of arm z^3 and contact a^3 and connects arms c^4 and z^3 , whereby the contacts a' on the bar c^2 will be electrically energized from line wire 2 through the following connection, namely: 40 Wire 52, arms c^4 and z^3 , wire 54, coil v^7 of switch w and wires 50, 34 and 10 to line wire 2. The throwing over to the left of switch arm c^4 causes a separation of the switch arm z^4 and contact a^4 .
- 45 The car is now traveling at full speed in a downward direction and the operator in order to effect a stop will push upon the controller handle d so as to bring the arm h^4 into contact with point h^3 . This causes the energization of wire 65 and a circuit is established through resistance v^6 and magnet coil v^7 of switch w , thence through wires 50, 34 and 10 to line wire 2. The effect of the current flowing is a partial energization of magnet coil v^7 , not sufficient to cause switch
- 50 arms w^3 , w^4 , and w^5 to be thrown, but sufficient to cause quick action when said coil is further energized as will be described. The wire 65 also energizes wire 67 and roller b^6 of traveling carriage S, which upon making contact with the nearest fixed contact a' on bar c^2 will cause current to flow through wire 52, arm c^4 of switch z , arm z^3 , wire 54 coil v^7 of switch w , wires 34 and 10 to line wire 2. This current through coil v^7 on account of its being already partly energized, causes very quick action of the switch w whereby the switch arms w^3 , w^4 and w^5 are thrown to their extreme left-hand position. The movement of arm w^3 causes a separation of arm 17 with respect to contact w^2 and thereby deenergizes magnet x which opens switch arm 30 and causes resistance s to be placed in series with field winding g of generator G. This causes the voltage in generator line wires 1' and 2' to drop, which causes magnet z' to release the arms c^3 , c^4 and c^5 . The effect of the releasing of the arm c^4 is to substitute vertical bar d^2 in place of c^2 on account of the wire 56 being connected to switch contact a^3 . This provides for the energization of magnet coil v^7 of switch w as soon as contact roller b^7 carried by carriage S contacts with the nearest contact a' of bar d^2 , through wires 65, 67, 69, contacts b^7 , a' , wire 56, contact a^3 , arms z^3 , wire 54, coil v^7 , wires 50, 34 and 10 to 2.
- 55 By reason of switch w being moved to the extreme left-hand position by action of magnet v^7 , circuits are closed for the preenergizing of magnets t and u through resistances 35 and 39, as follows: From line wire 1 through wires 3, 31, arm z^4 , contact a^4 , wire 33, resistances 35 and 39 in multiple and wire 37 and coil u in multiple with wire 41 and coil t to wire 38, wire 58, switch arm w^6 , arm w^4 , wires 60, 34 and 10 to line wire 2. The action of the traveling contact b^8 when it reaches the nearest contact a' on the vertical rod, e^2 is to complete the energizing of the magnet coil t sufficiently to operate the arm t^1 and cause the opening of the shunt formed by wires 18 and 20 so that the resistance s^1 will be thrown in series with resistance s and field winding g . This circuit is as follows: Wires 1, 3, 31, arm z^4 , contact a^4 , wire 33, rotating switch arm Q^1 , segment 71, wire 73 to contact a' on vertical bar e^2 , thence through roller b^8 of carriage S, wire 47, wire 41, coil t , wires 38 and 58, arms w^3 and w^4 , wires 60, 34 and 10 to line wire 2.
- 60 The next step in slowing down consists of the complete energization of magnet u for moving arm t^2 to left-hand position, thereby opening the shunt formed by wires 20² and 20' and inserting resistance s^2 in series with s^1 , s , and field winding g . This circuit is as follows: Wires 1, 3, 31, arm z^4 ,

contact a^4 , wire 33, rotating switch arm Q^1 , segment 75, wire 77, contact a' of vertical bar f^2 , roller b^9 of carriage S, wires 79, 53, 37, magnet coil u , wires 36, 38, 58, switch 5 arms w^6 and w^4 , wires 60, 34 and 10 to line wire 2.

The next step consists in bringing the hoisting motor to a stop by throwing the reversing switch D and applying the brake. 10 These functions are effected by the energizing of magnet coil i through the following circuit: Line wire 1, wires 3, 31, arm z^4 , contact a^4 , wire 33, rotating switch arm Q^1 , segment 81, wire 83, contact a' carried by vertical bar g^2 , roller b^{10} of traveling carriage S, wire 85, arms w^7 and w^5 , coil i and wire 10 to line wire 2. This causes the arm i^1 to be thrown to its left-hand position, thereby separating arm i^2 from contact i^3 which deenergizes the magnet f^3 of the reversing switch D by opening a circuit previously described. 20

The operations above described are those which take place in bringing the car to a stop from full speed. 25 In case full speed has not been reached at the moment when the controller handle d is pushed forward, as in descending from one floor to the next, the sequence of events will be similar to that 30 described in connection with the ascending of the car from floor to floor.

In the claims the term "slow down means" is intended to include means which slow down the car to a complete stop as 35 well as means which reduce its speed without stopping it.

We claim:

1. In an electric elevator system, a car and a contact movable in unison therewith, 40 a set of normally open car stopping circuits, one for each landing, and means under control of the operator for causing said movable contact to close one of said circuits to stop the car.

45 2. In an electric elevator system, a car and a member mechanically associated and movable in unison therewith, a set of normally open car stopping circuits, and means under control of the operator for causing 50 said movable member to effect the closing of one of said circuits to stop the car.

3. In an electric elevator system, a set of normally open car stopping circuits having 55 fixed members arranged in mechanical sequence corresponding to the various floor landings, and a traveling member moving in unison with the car and cooperating with the fixed members to close the car stopping circuits.

60 4. In an electric elevator system, a set of normally open car stopping circuits having fixed members arranged in mechanical sequence corresponding to the various floor landings, and a traveling member moving in 65 unison with the car and cooperating with

the fixed members to close the car stopping circuits, and means under control of the operator for causing the traveling member to effect the closing of one of said circuits to stop the car. 70

5. In an electric elevator system, an electric translating device for operating the elevator car and having a field winding, a resistance, an electromagnet to connect said resistance in series with said field winding 75 and automatic means for partially energizing said electromagnet when the speed of the moving car drops below a given rate.

6. In an electric elevator system, a car, slowing down means comprising a fixed contact and a contact movable in unison with the car, to engage the fixed contact, an electromagnet for controlling said slow down means, and means for partially energizing said magnet in advance of the engagement 80 of said fixed and movable contacts.

7. In an electric elevator system, a hoisting motor, means for controlling the speed thereof including an electromagnet, and automatic means for partially energizing said 90 magnet when the speed of the hoisting motor drops below a given rate.

8. In an electric elevator system, an elevator car, slow down means including a controlling electromagnet, manually controlled 95 means for partially energizing said magnet, and means moving in unison with the car for fully energizing said magnet.

9. In an electric elevator system, a car, a rotary contact movable in unison therewith, 100 a plurality of normally open slow down circuits adapted to operate in sequence to cause reduction of car speed, and fixed contacts associated with said slow down circuits for successive engagement by said rotary contact to effect the sequential closing of said slow down circuits.

10. In an electric elevator system comprising a car, a plurality of fixed contacts and a contact movable in unison with the car to engage the fixed contacts, of slow down means and means for connecting said fixed contacts therewith consisting of a rotary switch having a multiplicity of fixed contacts, a rotary arm to engage the same, and means for moving said arm in unison with 110 said car.

11. In an electric elevator system comprising a car, a plurality of fixed contacts and a contact movable in unison with the car to engage the fixed contacts, the combination of slow down means and means for connecting said fixed contacts therewith consisting of a rotary switch having a multiplicity of fixed contacts, a rotary arm to engage the same, and means for moving said arm in unison with said car at such speed that it will make at least one rotation while the car is moving from one landing to the next, 120 125

- the relation between the car and the arm being fixed.
12. In an electric elevator system, a car, a set of slow down circuits, one for each landing, each of said circuits being normally open at two points, means for closing said circuits at one of said points comprising a fixed contact for each landing and a contact movable in unison with the car to engage said fixed contacts, and means for closing said circuits at the other of said points comprising a fixed contact and a rotating contact to engage the same, said rotating contact moving in unison with the car. 70
13. In an electric elevator system, a plurality of fixed contacts corresponding to one floor landing, a corresponding number of movable contacts each cooperating with one fixed contact, means for moving the movable contacts in accordance with the movement of the elevator, and means controlled in accordance with the elevator speed for selectively impressing potential upon the fixed contacts as they are respectively engaged by the movable contacts. 75
14. In an electric elevator system, a plurality of fixed contacts corresponding to one floor landing, a corresponding number of movable contacts each cooperating with one fixed contact, means for moving the movable contacts in accordance with the movement of the elevator, an electro-magnet in control of the speed of the elevator and connectable in circuit with each contact of one kind of said contacts independently, and means controlled by the voltage of the elevator power circuit for selectively connecting the electro-magnet in circuit with contacts of the said one kind and causing the circuits to be energized. 80
15. In an electric elevator system, a plurality of fixed contacts corresponding to one floor landing, a corresponding number of movable contacts each cooperating with one fixed contact, means for moving the movable contacts in accordance with the movement of the elevator, an electro-magnet in control of the speed of the elevator and connectable in circuit with each of the fixed contacts independently, and means controlled in accordance with the elevator speed for selectively connecting the fixed contacts in circuit with the electro-magnet and causing the circuits to be energized. 85
16. In an electric elevator system, a plurality of fixed contacts corresponding to one floor landing, a corresponding number of movable contacts each cooperating with one fixed contact, means for moving the movable contacts in accordance with the movement of the elevator, an electro-magnet in control of the speed of the elevator and connectable in circuit with each contact of one kind of said contacts independently, means controlled in accordance with the elevator speed for selectively connecting the electro-magnet in circuit with contacts of the said one kind and causing the circuits to be energized. 90
17. In an electric elevator system, a plurality of fixed contacts corresponding to one floor landing, a corresponding number of movable contacts each cooperating with one fixed contact, a plurality of normally open circuits corresponding in number to the fixed contacts, each circuit including a fixed and movable contact, and means for causing said circuits to be energized when they are closed by the engagement of said fixed and movable contacts. 95
18. In an electric elevator system, a plurality of fixed contacts corresponding to one floor landing, a corresponding number of movable contacts each cooperating with one fixed contact, a plurality of normally open circuits corresponding in number to the fixed contacts, each circuit including a fixed and movable contact, and electromagnetic means for causing said circuits to be energized when they are closed by the engagement of said fixed and movable contacts. 100
19. In an electric elevator system, a plurality of fixed contacts corresponding to one floor landing, a corresponding number of movable contacts, a plurality of normally open circuits each including a fixed and movable contact, one of said circuits including an electro-magnet operative to control the closing of the other circuits by the engagement of their respective fixed and movable contacts and means for partially energizing said electro-magnet circuit in advance of the engagement of its respective fixed and movable contacts. 105
20. In an electric elevator system, a plurality of fixed contacts corresponding to one floor landing, a corresponding number of movable contacts, a plurality of normally open circuits each including a fixed and movable contact, one of said circuits including an electro-magnet adapted to control the closing of the other circuits by the engagement of their respective fixed and movable contacts, and means under the control of the operator for partially energizing said electro-magnet when its fixed and movable contacts are disengaged and for causing its full energization when its fixed and movable contacts are engaged. 110
21. In an electric elevator system, a plurality of fixed contacts corresponding to one floor landing, a corresponding number of movable contacts each cooperating with one fixed contact, means for moving the movable contacts in accordance with the movement of the elevator, a plurality of normally-open circuits corresponding in number to the fixed contacts, each circuit including a fixed and movable contact, and means including the fixed and movable contacts for 115
- 120
- 125
- 130

causing said circuits to be closed successively.

22. In an electric elevator system, a plurality of fixed contacts in stepped relation to each other and corresponding to one floor landing, a corresponding number of movable contacts each cooperating with one fixed contact, means for moving the movable contacts in accordance with the movement of the elevator, a plurality of normally open circuits corresponding in number to the fixed contacts, each circuit including a fixed and movable contact to be closed by the successive engagement of said fixed and movable contacts.

23. In an electric elevator system, a hoisting motor, a generator directly connected thereto, a variable resistance in the generator field circuit, a plurality of circuits for varying said resistance, an electro-magnet adapted to control said circuits, and means under the control of the operator for partially energizing the electro-magnet.

24. In an electric elevator system, a car, a rotary contact movable in unison therewith, a plurality of fixed contacts in circumferential relation to the movable contact, a plurality of normally open circuits, each circuit including the rotary contact and one fixed contact, and means including said fixed contacts for varying the closing of said circuits in accordance with the position of the car at a floor landing.

25. In an electric elevator system, a car, a rotary contact movable in unison therewith, a plurality of fixed contacts in circumferential relation to the rotary contact and corresponding to definite distances between landings, and a plurality of normally open circuits, each circuit including the rotary contact and one fixed contact to be closed by the engagement of said rotary and fixed contacts.

26. In an electric elevator system, a series of fixed contacts corresponding to the respective floor landings, a movable contact to engage the fixed contacts, a second series of fixed contacts, each contact of said first series of fixed contacts being connected to one of said second series of contacts, and a movable contact for said second series of contacts, and means for moving both of said movable contacts over their respective fixed contacts in a definite relation to the movement of the elevator car.

27. In an electric elevator system, a series of fixed contacts corresponding to the respective floor landings, a movable contact to engage the fixed contacts, means for moving the movable contact in accordance with the movements of the elevator car, a second series of fixed contacts, each contact of said first series of fixed contacts being connected to one of said second series of fixed contacts, and a movable contact for said second series

of fixed contacts, the movable contact of said second series of fixed contacts being movable over the fixed contacts in accordance with the movements of the first mentioned movable contacts over its fixed contacts.

28. In an electric elevator system, a series of fixed contacts corresponding to the respective floor landings, a movable contact adapted to engage the fixed contacts, a second series of fixed contacts, each contact of said first series of fixed contacts being connected to one of said second series of fixed contacts, a second movable contact adapted to engage said second series of fixed contacts, and means common to both of said movable contacts for moving said movable contacts in a definite predetermined relation to the movements of the elevator car.

29. In an electric elevator system, a plurality of fixed contacts corresponding to one floor landing, a corresponding number of movable contacts each cooperating with one fixed contact, a second series of fixed contacts, each contact of said first series of fixed contacts being connected to one of said second series of fixed contacts, and a movable contact for said second series of contacts, and means for moving the said first and second mentioned contacts in a definite relation to each other and to the elevator car.

30. In an electric elevator system, a plurality of fixed contacts in stepped relation to each other and corresponding to one floor landing, a corresponding number of movable contacts, each cooperating with one fixed contact, a second series of fixed contacts, each contact of said first series of fixed contacts being connected to one of said second series of fixed contacts, a movable contact for said second series of fixed contacts, means for moving the movable contacts of said first series of contacts in accordance with the movement of the elevator car, and the movable contact of said second series of contacts in definite relation to the movement of the first mentioned movable contacts, and a plurality of normally open circuits corresponding in number to the fixed contacts of the first series, each circuit including a fixed contact of both series and the movable contacts associated therewith and adapted to be closed by the simultaneous engagement of the movable contacts with the fixed contacts.

31. In an electric elevator system, a hoisting motor, a series of fixed contacts corresponding to the respective floor landings and means responsive to the voltage of the hoisting motor circuit for controlling the energization of said contacts.

32. In an electric elevator system, an elevator motor, a variable voltage generator directly connected thereto, a series of fixed contacts corresponding to the respective floor landings, and means responsive to the volt-

age supplied to the motor for controlling the energization of said contacts.

33. In an electric elevator system, an elevator car, slow down means including a controlling electromagnet, means for partially energizing said magnet, and additional means responsive to the voltage of the hoisting motor circuit for controlling the full energization of said magnet.

10 34. In an electric elevator system, an elevator car, slow down means including a controlling magnet, means for partially energizing said magnet, means moving in unison with the car for fully energizing said 15 magnet, and means responsive to the voltage of the hoisting motor circuit for controlling the full energization of said magnet.

20 35. In an electric elevator system, a hoisting motor, a generator directly connected thereto, a variable resistance in the generator field circuit, a plurality of normally open circuits for varying said resistance, electromagnetic means for closing each of said circuits and an electromagnet adapted to control the operation of said electromagnetic 25 means.

30 36. In an electric elevator system, a hoisting motor, a generator directly connected thereto, a variable resistance in the generator field circuit, a plurality of circuits for varying said resistance, an electromagnet adapted to control said circuits, means under the control of the operator for partially energizing the electromagnet, and 35 means responsive to the voltage in the hoisting motor circuit for controlling the full energization of the electromagnet.

37. In an electric elevator system, a plurality of fixed contacts corresponding to one 40 floor landing, a corresponding number of movable contacts each cooperating with one fixed contact, a plurality of normally open circuits corresponding to the number of fixed contacts, each circuit including a fixed and 45 movable contact, an electromagnet for causing said circuits to be energized when they are closed by the engagement of the fixed and movable contacts, and means under the control of the operator for partially energizing the electromagnet.

In witness whereof, we hereunto subscribe our signatures.
